CABLE CUTTING DEVICE

Francis J. Van Laanen, Jr., Green Bay, Wis., assignor to Green Bay Drop Forge Company, Green Bay, Wis., a corporation of Wisconsin

Application April 12, 1935, Serial No. 16,021

4 Claims. (Cl. 164—80)

This invention relates to improvements in cable cutting devices.

In recent years, particularly since the advent of the four-wheel brake, actuating power has been transmitted to vehicle brakes through the medium of flexible cables. This cable is usually formed of a plurality of twisted strands of high tensile strength, high carbon, tempered steel. Necessarily, this material cannot be easily cut, and therefore in assembling brake actuating mechanism, difficulties are encountered when it is necessary to sever a cable at a desired point. In my co-pending application Serial #8,616, a brake actuating device is disclosed wherein a cable, which is secured at one end to the brake in connection with one of the vehicle wheels, is attached to the equalizer shaft arm by means of a special fitting. In making said attachment, it is customary to first determine by experiment with one end of the cable secured to the brake, the approximate point at which the other end of the cable is to be severed. Heretofore it has been necessary to remove the cable entirely from the vehicle, after determining the length desired, place it in a slotted die, and then use a hack saw to make the cut. The hack saw method is objectionable however as in order to cut the extremely high tensile strength strands, expensive hack saw blades of high speed steel must be used. Furthermore, each blade will only stand up for about two cuts. The method is also objectionable as the hack saw tends to spread the strands, leaving a bulky end for insertion in a fitting. The use of an abrasive wheel is objectionable as it also tends to undesirably broom out the cable end. While this type of cable may be cut by a chisel or shear, these methods tend to depress or deform the cut end so that it cannot be inserted in a snug fitting aperture of an attachment member.

It is one of the objects of the present invention to provide a simple and durable cutting device which makes it possible to sever a brake assembly cable while one end of said cable is connected to the vehicle, and which cutting device is further adapted for general use in severing various types of cables, rods, or the like.

A further object of the invention is to provide a cable cutting device which is so constructed as to maintain the cut end in its original shape,—that is, it is adapted to sever a round cable, for example, without disturbing the true circular cross sectional shape at the cut end.

A more specific object of the invention is to accomplish the above purpose by providing means for maintaining and holding the cable in its

proper cross sectional shape to prevent brooming, and by providing a tool so shaped as to operate without causing distortion by compression.

A further object of the invention is to provide a cable cutting device which will also preserve the original shape of the end of the severed portion, so that said severed portion may be salvaged for future use.

A further object of the invention is to provide a device of the class described wherein the body is transversely slotted to facilitate the insertion of the cable therein, said slotted construction permitting cutting at either an intermediate or an end portion of the cable length.

Other objects of the invention are to provide a cutting device which is inexpensive, which will last for an indefinite period, which is of unusually convenient size, and which can be used without the aid of an auxiliary holding die.

With the above and other objects in view, the invention consists of an improved cable cutting device and all of its parts and combinations as set forth in the claims, and all equivalents thereof.

In the accompanying drawing in which the same reference numerals designate the same parts in all of the views,

Fig. 1 is a fragmentary side elevational view showing portions of a brake assembly, slightly in perspective, parts being shown in section, and the improved cutting device being shown in a position to sever the end of the cable;

Fig. 2 is a front elevational view of the cutting device, part being broken away and shown in vertical section;

Fig. 3 is a sectional view taken on line 3—3 of Fig. 2;

Fig. 4 is a perspective view of the cutting plunger; and

Fig. 5 is a side elevational view of the device showing how a handle may be used in connection therewith, part being broken away and shown in section.

Referring more particularly to the drawing, while the device is obviously capable of general use, Fig. 1 illustrates an adaptation for which it is particularly suited. In said figure, the numeral 6 designates the equalizer shaft of a vehicle, said shaft having a rigidly mounted arm 7 which extends in both directions from the shaft. One end of the arm is connected to a clevis 8 and said clevis may have threaded therein an extension stud 9 projecting from one end of a cable end clamping device 10. A cable 11 which has one end operatively connected to the brake 12 of the vehicle is adapted to have its other end se-

cured in the fitting 10. It is usual practice, in making said connection, to insert the end 13 of the cable loosely in the fitting 10 to determine where the end should be cut off in order to obtain a desired tautness in the cable assembly. With the present methods, after the point is determined and marked, it is necessary to disconnect the cable from the brake, take it to a work bench and place it in a holding die so that a 10 hack saw may be employed to make the desired cut. This method is obviously troublesome, and in addition, the hack saw method of cutting is highly objectionable. The brake cable, as before mentioned, is formed of a plurality of strands of high tensile strength, high carbon, tempered steel, and in order to cut material of this nature, expensive hack saw blades of high speed steel must be employed. The expense of this cutting is augmented because of 15 the fact that the blade will only stand up for about two cuts. Furthermore, the use of the hack saw tends to broom out the end of the cable so that insertion into the snug fitting bore of the cable clamp 10 is rendered difficult. If 20 a chisel or shear is employed for severing the cable in the place of the hack saw, the end is necessarily compressed or squeezed into elongated cross sectional shape so that it cannot be inserted in the cable clamp 10. The present invention makes it possible to perform this cut 25 while one end of the cable 11 is attached to the brake without brooming out or otherwise distorting the cut end so that said end may be readily inserted in the bore of the cable clamp 10.

The device comprises two principal parts, a 30 body 14 and a plunger 15, both formed of high grade tool steel. The body is preferably substantially circular in cross section and may have an inwardly tapered upper end portion 16. Said body is formed with a vertical bore 17 extending therethrough for slidably receiving the plunger 15. The body is also formed with a transverse slot or aperture 18 which intersects the vertical bore and which is substantially semi-circular in plan view so that the slot communicates with the front of the tool and with opposite sides thereof. The inner portion of the slot 18 is rounded as at 19 to conform substantially to the shape of the cable 11 to be inserted therein. (See Fig. 3.) While the major portion of the slot 18 has a thickness just slightly greater than the thickness of the cable to be inserted therein, there is one portion on one side of the vertical bore 17 which is depressed as at 21. 35

The plunger has its upper projecting end provided with an integral head 22 and has its lower end bifurcated as at 23, the inner portion of said bifurcation being rounded as at 24 to conform to the shape of the cable. The plunger 15 is also provided on one side with an elongated recess 23. A set screw 24 accessible exteriorly of the body, has its inner end projecting into the slot 23 as at 25 to thereby form a guide for maintaining the bifurcated lower portion of the plunger in proper alignment. If a handle is desired, such as the handle 26 shown in Fig. 5, the set screw 24 may be incorporated in the inner end of the handle.

In the use of the device, it may be positioned 70 on the garage floor in the manner shown in Fig. 1 and the end of the cable 11 which is to be cut, inserted therein so that the point on the cable which is to be cut aligns with the right hand side of the bore 17. (Referring to Fig. 2.)

The plunger is of course held in an upward po-

sition while the cable is inserted in the slot 18. The plunger is then permitted to fall into contact with the cable so that its bifurcation 23 embraces the portion of the cable spanning the vertical bore in the manner shown in Fig. 2 and 5 Fig. 3. Next, the head 22 of the plunger is struck by a relatively heavy mallet and this impact causes a shearing action to take place along the line 27 to sever the cable at this point. The cable is not severed on the other side of the 10 plunger due to the fact that the slot 18 is depressed as at 21. This depression permits the severed portion of the cable to drop to the bottom of the depression 21. Due to the fact that the inner portion of the slot 18 is shaped to conform to the shape of the cable, the latter is maintained in its original shape so that it will not broom out during the cutting operation. Furthermore, due to the fact that the plunger is not formed with a chisel edge or the like, there 20 is no squeezing of the cable during the cutting such as would deform the cut end and render it difficult to insert said end in the clamping device 10. The action is also such that the severed portion of the cable is cleanly cut so that this 25 portion may be salvaged for future use.

Due to the use of the slot 18 which communicates with the front of the device, the cable may be readily placed in position for cutting, whereas if merely a transverse bore were employed, to 30 intersect the vertical bore, then the cable would have to be threaded into the body and a cut could not be made unless there was a free end.

The nature of the material used in the cutting device is such that an unlimited number of cuts 35 can be made without affecting the device and therefore the device can be used repeatedly for an indefinite period.

While the cutting device is particularly adapted for use in connection with brake cables 40 as shown in Fig. 1, it can of course be advantageously employed in many other connections. The transverse aperture or slot may also be proportioned and shaped differently to take materials of different cross sectional shape or of different diameter and to hold said materials in proper shape so that the cut ends will not be distorted. It is also obvious that force may be applied to the plunger 15 in other ways than by a 45 striking impact on the head 22, as the device could easily be made in more complicated form to embody leverage or the like for aid in depressing the plunger. Various other changes and modifications may be made without departing from the spirit of the invention, and all such 55 changes are contemplated as may come within the scope of the claims.

What I claim is:—

1. A device for cutting a cable comprising a body portion having a vertical bore and having a slot extending laterally inwardly from the front of the device and terminating in a curved inner end portion which communicates with the vertical bore and which is offset downwardly on one side of said bore, the cable being insertable in 60 said slot and guided thereby to cutting position against said curved inner end, and a plunger 65 slideable in said vertical bore and having an upwardly projecting impact end, said plunger having its lower end formed with a vertically extending slot having a curved upper end portion, said plunger being movable to a position wherein the curved upper end of the plunger slot fits around a portion of the cable to cooperate with the curved inner end of the lateral body slot to 70 75

hold the cable in proper position and cross sectional shape prior to and during cutting.

2. A device for cutting a cable comprising a relatively small one piece body of tool steel having a vertical bore and having a slot extending laterally inwardly from the front of the device and terminating in a curved inner end portion which communicates with the vertical bore and which is off-set downwardly on one side of said bore, the cable being insertable in said slot and guided thereby to cutting position against said curved inner end, and a plunger slideable in said vertical bore and having an upwardly projecting impact end, said plunger having its lower end formed with a vertically extending slot having a curved upper end portion, said plunger being movable to a position wherein the curved upper end of the plunger slot fits around a portion of the cable to cooperate with the curved inner end of the lateral body slot in holding the cable in position, said cooperating curved slot portions being conforming in shape to the cable so that the cable maintains its original cross sectional shape after cutting.

25 3. A device for cutting an elongated member comprising a body portion having a vertical bore circular in cross section and also having a transverse aperture intersecting said bore and communicating with opposite sides of the bore, said aperture being shaped to receive the elongated member to be cut, and a plunger circular in cross section slideable in said vertical bore and having an upwardly projecting end, said plunger having

a side vertical groove and having its lower end bifurcated to embrace the portion of the elongated member spanning the vertical bore and being adapted to cooperate with the body in shearing said elongated member in response to applied force on the projecting end of the plunger, and means removably insertable in the body for cooperation with the vertical groove of the plunger to prevent rotation of said plunger and thereby maintain the bifurcated end in proper alignment.

4. A device for cutting an elongated member comprising a body portion having a vertical bore circular in cross section and also having a transverse aperture intersecting said bore and communicating with opposite sides of the bore, said aperture being shaped to receive the elongated member to be cut, and a plunger circular in cross section slideable in said vertical bore and having an upwardly projecting end, said plunger having a side vertical groove and having its lower end bifurcated to embrace the portion of the elongated member spanning the vertical bore and being adapted to cooperate with the body in shearing said elongated member in response to applied force on the projecting end of the plunger, and a handle having its inner end removably insertable in a side of the body and cooperable with the groove of the plunger to prevent rotation of the plunger and thereby maintain the bifurcated end in proper alignment.
